UNITED STATES PATENT OFFICE.

IRA M. DAVIDSON, OF NEELEYVILLE, MISSOURI, ASSIGNOR OF ONE-FOURTH TO
WILLIAM B. DAVIS, OF NEELEYVILLE, MISSOURI, AND ONE-FOURTH TO
COLUMBUS I. DAVIS, OF CLINTON, MISSOURI.

SPARK-GENERATOR FOR INTERNAL-COMBUSTION ENGINES.

1,015,788.

Specification of Letters Patent.

Patented Jan. 30, 1912.

Application filed April 25, 1911. Serial No. 623,296.

To all whom it may concern:

Be it known that I, IRA M. DAVIDSON, a citizen of the United States, residing at Neeleyville, in the county of Butler and 5 State of Missouri, have invented certain new and useful Improvements in Spark-Generators for Internal-Combustion Engines, of which the following is a specification.

10 My invention relates to devices for generating the sparks in internal combustion engines and to the class of sparkers employing induction coils with means to control the current in the primary circuit, and 15 has for its object the provision of a device that is simple in construction and operation and that is economical in the consumption of electricity, producing but a single spark for each charge so timed as to occur at exactly the right time in all of the cylinders, and one in which the length of spark may 20 be varied to suit the conditions of the engine and the spark generator, and one in which the length of spark is the same at high or low speeds, the closing of the spark 25 circuit being effected by a spring actuated device that works at the same speed under all conditions of motor speed.

My invention will be described in detail 30 hereinafter and illustrated in the accompanying drawings in which—

Figure 1 is a vertical sectional view of my improved spark generator, showing the electric generator, spark coil and circuits 35 diagrammatically, Fig. 2, a top plan view, Fig. 3, a plan view of the mechanism for controlling the primary circuit in the position of the operating mechanism when at rest, Fig. 4, a view similar to the view in 40 Fig. 3 showing the operating mechanism when actuated by the engine shaft, Fig. 5, a view similar to the view in Fig. 3 showing the operating mechanism at the moment it is released by the shaft, and Fig. 6, a view 45 similar to the view in Fig. 3 showing the operating mechanism at the moment when closing the primary circuit.

In the drawings similar reference characters will be used to designate correspond- 50 ing parts in the several views.

My improved generator is mounted on a bracket 1 secured to any suitable support such as the casing of the engine (not shown).

2 indicates the lower portion of the generator casing that is constructed of metal and has a central tubular extension 3 secured on bracket 1.

4 indicates a circular plate seated in the casing 2 and having a central tubular extension 5 that is revolvably mounted in tubular extension 3 and extended below its lower end, and has an operating handle 6 secured thereto to control the advance and retarding of the spark.

7 indicates a shaft journaled in tubular extension 5 and when in position geared to the power shaft of a two cycle engine or the cam shaft of a four cycle engine.

8 indicates a collar secured to the shaft 7 and engaging the lower end of the tubular extension 3 to prevent upward movement of the shaft, cam wheel 9 secured to the shaft and bearing against the upper side of plate 4 holds the shaft from downward movement.

The upper portion of the casing consists of a ring 10 of non-conducting material such as vulcanized rubber, fiber or the like and a top plate 11, of the same material, secured thereto.

12 indicates a contact button secured in the center of plate 11 and 13 other contact buttons secured near the edge of said plate, one button for each cylinder in the motor to which the generator is connected, said buttons being arranged equidistant from one another.

14 indicates the distributor head made of a non-conductor of electricity mounted on the upper end of shaft 7 and rotatable therewith by means of a cross-pin 15 in the head engaging a slot 16 in the upper end of the shaft. Distributer head 14 is formed with a laterally extending arm 14^a and 17 indicates a contact strip secured to the upper side of distributor head 14 and arm 14^a and adapted to close the circuit between contact button 12 and contact buttons 13 in turn.

A indicates a spark coil of ordinary structure having one of its primary terminals connected by wire B with a battery or other suitable generator of electricity C, and its other primary terminal connected by wire D with a binding post 18 secured to the lower portion 2 of the spark generator casing.

E indicates a wire from the generator C that is grounded on bracket 1.

F indicates the wire connecting the secondary terminal of the coil A and contact button 12, and G the wires connecting buttons 13 with the spark plugs of the several engine cylinders (not shown).

19 indicates a conductor ring mounted within the lower portion 2 of the casing, 10 and separated therefrom by means of insulation 20, said ring being secured to binding post 18 so that it is in circuit with the primary of coil A through conductor wire D.

21 indicates a plate secured to circular 15 plate 4 and insulated therefrom, 22 a slide bearing mounted thereon, and 23 a spring actuated brush mounted in slide bearing 22 and engaging ring 19.

24 indicates a post mounted on plate 21 10 with a contact screw 25.

26 indicates a lever pivotally mounted on plate 4, 27 a post secured to plate 4 and 28 a screw pin mounted in the post that limits the movement of said lever, 29 indicating 25 a spring that holds the lever normally in engagement with screw pin 28.

30 indicates a spring arm secured to lever 26 and 31 a contact point mounted on said arm and positioned to engage the contact point on the end of contact screw 25.

The end of lever 26 is formed with an inclined or barbed head 32.

33 indicates a spool-shaped wheel journaled on post 34 secured to plate 4, 35 a 35 pawl pivotally mounted in the wheel 33 and adapted to engage the barbed head 32 of lever 26, and 36 another pawl pivotally mounted on the wheel 33 and engaging cam wheel 9.

40 Cam wheel 9 is formed with as many cam notches 37 as there are cylinders in the motor so that when the shaft 7 makes a complete revolution the wheel 33 is rocked as many times as there are cylinders in the motor, it being apparent that as the shaft 7 and cam wheel 9 rotate in the direction indicated by arrow *a* that the pawl 36 will engage the cam notches 37 and move the spool-shaped wheel in the direction indicated by the arrow *b*. When the wheel is rotated by engagement of the pawl 36 with the cam notches aforesaid the pawl 35 passes barbed head 32 without lifting the lever, the spring 38 connecting pawls 35 and 36 55 returning the pawl 35 to engagement with stop pin 39 as soon as it has passed from engaging the head 32. Immediately after this the cam 9 is turned so that the pawl 36 is disengaged from cam notch 37 and 60 the wheel 33 is returned to its original position by means of coil spring 40. When the wheel is returned to its original position the pawl 35 being held from movement rearwardly by stop pin 39 and by engaging the 65 inclined face of the head 32 of lever 26

moves it against the resistance of spring 29 so that the contact point 31 on spring arm 30 engages contact screw 25.

When the contact point 31 engages contact screw 25, as above stated, the primary 70 circuit is closed from generator C, through conductor B, the primary winding in coil A, conductor D, binding post 18, conductor ring 19, brush 23, bearing 22, plate 21, post 24, contact screw 25, contact point 31, spring arm 30, plate 4, casing 2, bracket 1, and conductor E to the battery.

When pawl 35 finally slips off the end of barbed head 32 the lever 26 is returned to its normal position engaging screw 28 and 80 the primary circuit is broken. This breaking of the primary circuit causes a rise in potential in the secondary circuit which is communicated from coil A, through conductor F to button 12, thence through contact strip 17, one of the buttons 13 and its conductor G to the cylinder having a compressed charge ready to be fired; the distributor head being so mounted on shaft 7 that its arm 14^a is in proper position at the 90 moment of the rise in potential in the secondary of coil A, hereinbefore referred to, to close the secondary circuit to the cylinder to be fired.

41 indicates a pin secured to plate 4 and 95 42 a notch in wheel 33 that operates to limit the rocking movement of the wheel, and 43 a pin secured to wheel 33 and 44 a lug on the end of pawl 36 to limit the outward movement of the pawl under the influence of the 100 spring 38.

It will be apparent that as the length of closure of the circuit in the primary is governed by the speed of the return of wheel 33 to its normal position under impulse of 105 spring 40, that the operation of the spark is independent of the speed of the motor shaft and the size of the spark is the same whether the motor shaft be going at high or low speed, and the danger of missing 110 explosions and the consequent waste of unused gas is avoided. Furthermore the length of the primary impulse may be regulated, as desired by the engineer, by adjusting screw 28 so that the position of the lever 115 may be nearer to or farther away from the pawl 30 when it engages the barbed head 32, by adjusting the contact screw 25 so that its engagement with contact point 31 may be long or short. This construction and operation admits of using battery cells for a longer period than possible with other sparking devices as by actual experiment I have found it possible to make a spark with my apparatus with a battery testing one-half ampere and have obtained a spark with a battery showing only one-quarter ampere.

Having thus described my invention what I claim is—

1. A circuit breaker for spark generators 130

comprising a contact post, a spring held contact lever, a wheel rotatably mounted, pawls pivotally secured to said wheel, one of said pawls being adapted to engage the lever to move it into engagement with the contact post, a shaft, and a cam secured to the shaft and engaging the other pawl to actuate the wheel aforesaid.

2. A circuit breaker for spark generators consisting of a contact post, a spring held contact lever having its free end provided with a barbed end, a wheel rotatably mounted, pawls pivotally secured to said wheel, one of said pawls being adapted to engage the barbed end of the lever, a shaft, a cam on said shaft and engaging the other pawl on the wheel to rotate the wheel in one direction, and a spring secured to the wheel to return it to its normal position.

3. A circuit breaker for spark generators comprising a casing, a plate rotatably mounted in said casing, a contact ring secured to the side wall of the casing, a plate secured to the rotatable plate aforesaid and

insulated therefrom, a spring brush mounted on the last mentioned plate and engaging said contact ring, a contact post mounted on said plate, a spring held contact lever pivotally secured to the rotatable plate and having a barbed end, a wheel revolvably mounted on the rotatable plate, pawls pivotally secured to said wheel, one of said pawls adapted to engage the barbed end of the lever and move it into engagement with the contact post aforesaid, a shaft journaled on the rotatable plate, a cam on said shaft and adapted to engage the other pawl on the wheel to rotate the wheel in one direction, and a spring secured to the wheel and rotatable plate to return the wheel to its normal position.

In testimony whereof I hereto affix my signature in the presence of two witnesses.

IRA M. DAVIDSON.
